UNITED STATES PATENT OFFICE.

CHARLES WERNER, OF PINE GROVE, PENNSYLVANIA.

VALVE-GEAR FOR GAS-ENGINES.

SPECIFICATION forming part of Letters Patent No. 651,683, dated June 12, 1900.

Application filed September 14, 1899. Serial No. 730,483. (No model.)

To all whom it may concern:

Be it known that I, CHARLES WERNER, of Pine Grove, in the county of Schuylkill and State of Pennsylvania, have invented a new and Improved Valve-Gear for Gas-Engines, of which the following is a full, clear, and exact description.

My invention relates to an improvement in gas or explosion engines, and comprises the novel features which are hereinafter described and claimed.

Reference is to be had to the accompanying drawings, forming a part of this specification, in which similar characters of reference indicate corresponding parts in all the figures.

Figure 1 is a side elevation of my engine with a portion of the cylinder broken away to show the firing-chamber. Fig. 2 is a plan of my engine. Fig. 3 is a side elevation of the cylinder end of the engine with a portion of the cylinder broken away, showing the parts in the position in which the exhaust-valve is opened for the discharge of the burned gases. Fig. 4 is a similar view to Fig. 3, but showing the parts in the position for recharging the cylinder with explosive mixture. Fig. 5 is a section through the mixing-chamber, showing in elevation the mechanism for operating the cams and the governor; and Fig. 6 is an end elevation of the cylinder and the means for operating the various valves.

My engine belongs to that type of gas-engines commonly spoken of as "four-cycle" engines, or those in which an explosion is produced at every alternate revolution of the shaft. The cylinder A' is a trunk-cylinder—that is, is open at one end and uses only one end of the cylinder for the production of power. The piston C' therein is connected, by means of a connecting-rod C', with a center crank, formed upon the crank-shaft C, which is mounted upon the opposite end of the cylinder frame or bed A. Upon one side of the cylinder is formed a chamber A², similar in some respects to the steam-chests of an ordinary engine and having within the same a mixing and explosion chamber a. The gas is admitted to this mixing-chamber by means of valves K, which, as herein shown, are ordinary plug-valves mounted to reciprocate within their chambers, and thus to admit the gas to the mixing-chamber. These valves are di-

rectly operated by means of a bell-crank lever K², which is forked at one end, so as to connect with each of the valves K. Two valves K are herein shown, although one valve might answer the purpose. These valves are mounted to slide within cylindrical bosses K', formed upon the end of the chamber A².

The air is admitted to the mixing-chamber a through a valve E, which opens inwardly and is adapted to be held upon its seat by the pressure of gas within the chamber. This valve has a stem E², which extends outward through suitable bearings, and at its outer end has an elbow-shaped lever or arm e secured thereto, preferably by pivoting, as shown in the drawings.

Between the outer ends of the stem E² and the end of the mixing-chamber is inserted a spirally-coiled spring E³, which acts upon said valve-stem to normally hold the valve closed. The outer or free end of the arm e, which is secured to the outer end of the valve-stem, has a tooth or projection e², which is adapted to be engaged by a tooth or projection d' upon the end of a rod D, so that the arm e and the valve connected therewith may be drawn backward or toward the shaft of the engine, so as to open the valve and permit the introduction of air to the mixing-chamber. The arm e passes between guides e', which hold it securely in place and while permitting a slight rising-and-falling motion of the arm prevent its movement sidewise.

The exhaust-valve, which is located at one side of the mixing-chamber, is mounted upon the lower end of a stem J, which passes upward and has a spiral spring J' mounted thereon and adapted normally to hold said valve closed. This valve is one which opens inwardly after the same style as the air-admission valve E. The spring J' therefore tends to hold said valve closed. This valve is opened by the action of a lever I, which is pivoted upon the upper end of a standard I' and has one end entering a slot in the valve-stem J or secured thereto in any other suitable manner.

Mounted in suitable bearings beneath the lever I and extending in the same direction is a shaft H², upon one end of which is secured a ratchet-wheel H and upon the other end of which is secured a star or cam wheel,

H'. The ratchet-wheel H is provided with twice as many teeth h as there are toothed cam projections h' upon the star-wheel H'. The ratchet-wheel H will not engage the lever I, while the star-wheel H' is of such a size that when the toothed projections h' extend upwardly they will engage and raise the lever I. These parts are so proportioned that the partial turning of the shaft H² due to the movement of the ratchet-wheel through the space of one tooth will not cause the star or cam wheel to act upon the lever I, while the next movement of the ratchet-wheel through the space of one tooth will cause the star-wheel to lift the lever I, for the reason that this last movement will bring the extreme outer portion of the projection h' beneath the lever I. The ratchet-wheel H is operated by means of a rod B², which is, in effect, an eccentric-rod having upon its opposite end an eccentric-strap B', which passes about an eccentric B, which is secured to the engine-shaft. The end b² of the rod B² is turned up slightly and placed in such position that it will engage the teeth of the ratchet-wheel when reciprocated. The rod B² has an arm b' projecting therefrom and forming a guide for one end of a rod L, which at the other end is connected with the bell-crank lever K², by which the gas-admission valves are operated. This rod L has two tappets L' and L² mounted thereon, the tappet L' being screw-threaded thereon and adjustable in position. Between the tappet L², which is at the outer end of the rod, and the arm b' is placed a spirally-coiled spring L³, by which a yielding connection is made between the two rods L and B², so that when the arm b' strikes the spring it will cause the rod L to start smoothly and without any jerk. This construction also causes the movement of the rod L and the valves K, which are operated thereby, to be confined to a small portion of the reciprocating movement of the rod B², from which motion is obtained. Upon the rod B² is a second arm b, to the outer end of which is pivoted the rod D, which extends over the valve-operating mechanisms and is provided with means for operating both the firing-pin and the air-admission valve. The firing-rod F passes downward through the upper wall of the mixing-chamber and is provided with an arm f within said chamber, adapted to engage the fixed firing-pin f'. The firing-rod F is normally held raised or out of contact with the co-operating firing-pin f' by means of the spiral spring F', which surrounds the upper outer end of the rod F.

A lever G is mounted upon a pivot g and has three arms G', G², and G³. The arm G' engages the upper end of the firing-rod, while the arm G² extends upwardly, where it may be engaged by a notch or shoulder d upon the bar D. When the bar D reciprocates toward the right as the mechanism is shown in Figs. 1, 3, and 4, it will, if lowered to the proper position, engage the upper end of the

arm G², and thus cause the lever G to be swung upon its pivot, so as to depress the rod F, carrying the firing-pin. The arm G³, which extends in substantially-opposite direction from the arm G', is adapted to engage the under side of the rod D, and thus to free the rod and lever when the lever has been moved a proper distance. This permits the spring F' to quickly raise the firing-rod.

The outer end of the rod D has a downwardly-curving section D', which terminates in a tooth d', adapted to engage the tooth e² upon the lever e, and thus to open the air-admission valve. The outer end D' of this rod passes through suitable guides d², which retain it in proper position.

The vertical position of the rod D is determined by the position of the lever I. This lever has an extension which projects beneath the rod D. This extension, as herein shown, consists of a pivoted link I², the lower end of which is hooked or curved so as to pass beneath the rod D. When the shorter radius of the star or cam wheel H' is beneath the lever I, the rod D is in its lowermost position and will consequently engage the arm G² to depress the firing-pin when the rod is reciprocated toward the outer end of the cylinder. In this position the pointed outer end of the rod D will pass beneath the end of the arm e and lift it from the position shown in Figs. 3 and 4 or into the position shown in Fig. 1. To insure this action, the ends of the rod and arm are made sloping, as indicated in the drawings. When, however, the longer radius of the star or cam wheel H' is beneath the lever I the rod D will be raised, so that it will not engage the arm G² and will also be carried above the end of the arm e when reciprocated toward the outer end of the cylinder. This position is shown in Fig. 3. As soon as the star or cam wheel has been moved so that the lever I drops off of the outermost projection thereof the rod D will be dropped into the position shown in Fig. 4. This will engage the teeth d' and e², so that as the rod D is reciprocated backward or toward the engine-shaft it will draw the arm e back with it, and thus open the air-admission valve E. At the same time the rod L is carried back with the rod D and opens the gas-admission valves, so that the cylinder is recharged.

Upon the mixing-chamber is mounted a bell-crank lever O, which is pivoted thereon at O², as shown in Fig. 5. This lever has one end thereof extending upwardly and close alongside of the lever I. At its upper end it has a notch O' formed therein at such an elevation that it may engage the lever I when the latter is in its uppermost position, if the arm O be swung toward said lever. This arm is controlled by means of a governor N', the central spindle or shaft N of which extends downwardly and engages the arm O³ of the bell-crank lever O, so as to swing the upper end of the lever beneath the lever I. When the governor reaches the limit of the speed

desired, it will force the spindle N downward and swing the lever O toward the lever I, so as to engage the lever I and hold the bar D raised from engagement with both the lever 5 which operates the firing mechanism and with the arm which operates the air-admission valve. As a consequence the explosive mixture will not be introduced to the cylinder until the speed of the governor has dropped 10 to such a point as to release the lever I. The governor is operated in the usual manner by means of a belt N², which is operated from the engine-shaft or any other suitable revolving part of the engine.

15 The shaft H², upon which the star-wheel H' and the ratchet-wheel H are secured, has a spiral spring H³ surrounding the same between the ratchet-wheel H and the standard H', in which one end of the shaft is mounted. 20 This holds the ratchet-wheel H up against the other standard I' with sufficient force to create the friction necessary to prevent backward movement of the ratchet-wheel.

Having thus fully described my invention, 25 I claim as new and desire to secure by Letters Patent—

1. In a gas-engine, a spring-closed air-admission valve, an arm secured thereto and provided with a hook or catch, a rod having 30 a hook adapted to engage the hook on the arm of the air-admission valve, means for reciprocating said rod from the engine, an exhaust-valve and means for operating it, and means controlled by the exhaust-valve-operating mechanism whereby the engagement of the reciprocating rod with the air-admission valve is controlled and made to follow the opening of the exhaust, substantially as described.

40 2. In a gas-engine, a spring-closed air-admission valve, an arm pivoted thereto and provided with a tooth or catch, a valve-operating rod and means for reciprocating it in unison with the engine, said rod having a tooth adapted to engage the tooth upon the arm secured to the valve, and means for moving said rod out of engagement with said arm at each alternate stroke of the engine, substantially as described.

45 3. In a gas-engine, a spring-closed air-admission valve, an arm pivoted thereto and provided with a tooth or catch, a valve-operating rod, and means for reciprocating it in unison with the engine, said rod having a tooth adapted to engage the tooth upon the arm secured to the valve, and means for shifting the end of said rod so as to alternately pass above and below said arm whereby said arm and its valve is reciprocated only at each 55 alternate stroke of the engine, substantially as described.

50 4. In a gas-engine, a spring-closed valve, a pivoted arm having one end connected with the valve, a star-wheel or cam adapted to engage the other end of said arm to raise it and thereby open the valve, a tooth or ratchet-wheel connected with said wheel or cam and

having double its number of teeth, and a rod having an eccentric driving connection with the engine-shaft, and adapted to engage with 70 its free end the teeth of said ratchet-wheel to turn it, substantially as described.

5. In a gas-engine, an air-admission valve, a reciprocating rod for opening said valve, a firing-rod projecting into the firing-chamber, 75 a spring normally holding the rod out of firing position, a pivoted lever engaging the firing-rod and adapted to be engaged by the reciprocating rod to operate it, and means for holding said rod out of engagement with the 80 lever at each alternate movement thereof, substantially as described.

6. A gas or explosion engine, having separate gas and air admission valves, an exhaust-valve and a firing-pin, the exhaust-valve, the 85 air-admission valve and the firing-pin being spring-held in inoperative positions, a main valve-operating rod having reciprocative connection with the engine as by an eccentric, an auxiliary rod operated from said main 90 rod by tappets and operating the gas-admission valves, a pivoted lever connected with the exhaust-valve to open it, a star or cam wheel adapted to actuate said lever and exhaust-valve, a toothed or ratchet wheel connected with said wheel or cam and having double its number of teeth and adapted to be engaged by the end of the main valve-operating rod to be turned thereby, a pivoted firing-pin-operating lever having an upwardly-projecting arm, a toothed arm or bar secured to the air-admission valve, a rod connected with the main valve-operating rod and adapted to be engaged by an extension of the exhaust-valve-operating lever to be raised 105 and lowered, said rod passing over the firing-pin-operating lever and having a shoulder or projection adapted to engage an arm thereof to operate it on the outward stroke, the outer end of said rod dropping downward and 110 having a hook or tooth adapted to engage the tooth upon the arm which is secured to the air-admission valve, substantially as described.

7. In a gas-engine, a rod having reciprocative connection with the engine and operating the sparking and admission devices, a pivoted lever adapted to engage said bar to raise it to prevent its operation upon the said sparking and admission devices, means for periodically 120 raising said lever, a pivoted catch-lever adapted to engage said bar to hold it raised but normally acted upon to be cleared therefrom, and a governor having connection with said catch-lever to swing it into engagement 125 with said rod to hold it raised, substantially as described.

8. In a gas-engine, a spring-closed exhaust-valve, a pivoted arm connected thereto, a star-wheel or cam adapted to engage said arm to 130 open the valve, a toothed or ratchet wheel connected with the star-wheel to turn it, a rod having an eccentric driving connection with the engine-shaft and adapted to engage the

- teeth of said ratchet-wheel to turn it, an air-admission valve, a firing mechanism, a rod connected to reciprocate with the rod which turns the ratchet-wheel, and an extension of the arm which operates the exhaust-valve and engaging said last-mentioned rod to raise and lower it to cause it to operate said air-admission valve and firing mechanism at alternate reciprocations, substantially as described.
10. In a gas-engine, the combination with an exhaust-valve, a reciprocating rod, and means for operating the said valve from the rod, of gas-admission valves, a bell-crank lever connected with the gas-admission valves, and a rod carried by the reciprocating rod and connected with the bell-crank lever, substantially as described.
10. In a gas-engine, the combination with an exhaust-valve, a reciprocating rod, and means for operating the valve from the rod, of gas-admission valves, a rod having at one end a yielding connection with the reciprocating rod, and a connection between the other end of the rod and the gas-admission valves, substantially as and for the purpose set forth.
11. In a gas-engine, the combination with an exhaust-valve, a reciprocating rod provided with an apertured arm or lug, and means for operating the said valve from the rod, of gas-admission valves, a bell-crank lever connected with the said valves, a rod having one end connected with the bell-crank lever, and its other end working in the aperture of the arm or lug of the reciprocating rod and provided with tappets, and a coiled spring on the

rod between the arm and the tappet at the end of the arm, substantially as described.

12. In a gas-engine, the combination of a spring-pressed exhaust-valve, a pivoted lever connected with said valve, a wheel having cam projections for engaging the lever, means for operating the wheel from the engine-shaft, a spring-pressed air-admission valve, a toothed arm pivoted to said valve, a reciprocating rod having a tooth for engaging the tooth of the said arm, said rod being operated by the means operating the cam-wheel, and means for moving said rod out of engagement with the said arm at each alternate stroke of the engine, substantially as described.

13. In a gas engine, the combination of a spring-pressed exhaust-valve, a pivoted lever engaging the stem of said valve, a wheel having cam projections engaging the lever, a ratchet-wheel connected with the cam-wheel, a reciprocating rod operated from the engine-shaft and having its free end engaging the ratchet-wheel, a spring-pressed air-admission valve, an arm pivoted to the stem of the said valve and provided with a tooth, a rod carried by the reciprocating rod and provided with a tooth engaging the tooth of the said arm, and a pivoted link carried by the lever engaging the exhaust-valve stem, said link engaging the rod which operates the air-admission valve, substantially as described.
